BULB HOLDER FOR FLASHLIGHTS

Giles C. Fullmer, Bridgeport, Conn., assignor to
 The Bridgeport Metal Goods Manufacturing
 Company, Bridgeport, Conn., a corporation of
 Connecticut

Application December 13, 1935, Serial No. 54,190

9 Claims. (Cl. 173—358)

This invention relates to new and useful improvements in lighting devices and has particular relation to a bulb holder for flash lights.

An object of the invention is to provide a bulb holder for flash lights and which serves to hold a bulb straight and prevents it from getting loose and rattling.

Another object is to provide a holder particularly adapted for holding so called cat's eye bulbs, and in which the top or outer portion of the holder provides or comprises a reflector.

A further object is to provide a bulb holder comprising a pair of parts to clampingly hold a bulb without the use of the usual threads on the base of the bulb, and which holder is adapted to be threaded into a flash light casing to mount the bulb therein.

Other objects and advantages will become apparent from a consideration of the following detailed description taken in connection with the accompanying drawing wherein there is shown satisfactory embodiments of the invention. However, it is to be understood that the invention is not limited to the details shown but includes all such variations and modifications as fall within the spirit of the invention and the scope of the appended claims.

In the drawing:

Fig. 1 is a side elevational view of a complete flashlight of the so called pen light type, with portions broken away to show the manner of mounting the bulb and also showing the switch;

Fig. 2 is a view partly in side elevation and partly in section showing the improved holder;

Fig. 3 is an end elevational view of the holder of Fig. 2;

Fig. 4 is a view similar to Fig. 2 but showing a slightly different construction; and

Fig. 5 is an end elevational view with parts broken away showing the holder of Fig. 4.

Referring in detail to the drawing a tubular metal flash light casing is generally designated 10 and the same is provided with a clip 11 whereby it is adapted to be carried and secured in a pocket or the like in a manner similar to that of a fountain pen. The casing contains a battery 12 and in one end portion a switch 13 particularly shown and described in Abbott's Patent No. 1,919,024 of July 18, 1933. Into the other end of the casing there is inserted or fitted my improved holder 14 supporting a bulb 15.

The bulb 15 is of the new type known as a cat's eye bulb, and comprises a screw threaded base 16 from the outer end of which projects the center contact 17 of the bulb. Globe portion 18 of the bulb is somewhat tapered and is quite

small at its outer end in which is a small lens 9. In flash lights as heretofore constructed the base of the bulb is ordinarily threaded into a stem like portion of a reflector of drawn sheet metal of thin gauge, and due to the thin metal and the fact the thread is rolled in this thin metal the bulb may not be securely held, and further is not always held straight since the stem portion of the reflector may be easily bent relative to the body portion thereof.

According to the present invention the bulb is clamped in and supported by a holder which is not drawn to a diameter to have the bulb threaded into it, and in the present instance the threads on the bulb base are not used in securing the bulb in place. The holder is of a diameter to fit into the flash light casing without the latter being drawn in or having its diameter reduced. Such holder comprises a two part construction and the bulb is held by being clamped between said parts. As the description proceeds it will become clear that the holder may take a variety of forms but two of which are shown in the drawing.

Figs. 1, 2 and 3 show the holder 14 comprising the front and rear parts 19 and 20. Each may be of sheet metal and have screw threads rolled or pressed into its side walls whereby the rear part may be threaded into the front part to detachably connect the parts, and whereby the complete holder may be threaded into the end of the casing 10. Each part includes an end wall, although since part 19 tapers toward its forward end its wall 21 is of small area. Part 20 being substantially straight across its inner end its wall 22 is of appreciable area.

End wall 22 is provided centrally with an opening 23 of a diameter to permit of the passage therethrough of the insulation 24 and the center contact 17 of the bulb. However, the hole 23 is of less diameter than the threaded portion of the bulb base 16 so that the said metal base or screw contact is engaged by the end wall 20a of part 20 about the opening 23 whereby to ground the bulb base and to assist in mounting the bulb as will later appear.

Part 19 has its end wall provided with an opening and the material of the part about the opening inclines inwardly as shown at 25 whereby to have the outer surface of said portion form a reflector. Also, this portion 25 has its inner edge defining the diameter of the opening in the end of the part 19, and such opening is of less diameter than the globe portion of the bulb. Therefore when the parts 19 and 20 are assembled about a bulb the inner edge of the reflector

portion 25 engages the globe portion of the bulb as shown.

In the assembly a bulb is placed in the parts 5 19 and 20 and they are threaded together, care being taken to have the center contact of the bulb pass through opening 23 in the end wall of part 20 and to have the globe portion of the bulb partly enter the opening on part 19. The parts are screwed together until the globe portion 10 of the bulb is pressed against the inner edge of the reflector portion 25 while the base of the bulb is in engagement with the end wall portion 20a of part 20 about the opening 23. Obviously with such construction the bulb is 15 clamped between the parts but may be replaced on separation of the parts by unscrewing them.

After a bulb is mounted in the holder it is securely held without any strain on the bulb and without threading the bulb into place. With the 20 bulb in the holder the latter is threaded into the end of the casing to bring the center contact of the bulb into engagement with the center contact of the battery as shown in Fig. 1. For cooperation with the threads of the holder a thread 26 25 is rolled into the casing 10 adjacent the end thereof. A shoulder 27 on the holder limits the distance the latter may be threaded into the casing.

When the bulb and battery are in the casing as 30 in Fig. 1, on pressing inwardly on the button 28 the spring 29 engages the exposed end of the battery closing a circuit through the battery and bulb to energize the latter. A disc of insulating material 30 is held against the battery by a spring 31 and the battery is thus held in a forward position to maintain its center contact in engagement with the center contact 17 of the bulb. The washer 30 may move or float between the beads 32 whereby to accommodate batteries of slightly 35 different lengths.

Figs. 4 and 5 show a two part holder 33 the forward portion 34 of which is of a shape contrasting with that of the forward part 19 of the holder of Figs. 1, 2 and 3. However, holder 33 40 includes the inner or rear portion 20 previously described. Part 34 beyond its screw threaded portion is enlarged, but in its forward end wall is provided with an opening 35 into which the bulb 15 partly enters. A portion of the material of the part about the opening 35 is directed inwardly providing a flange 36 the surface of which may be a reflector as in the first form, and the inner edge of which engages the bulb 15 as shown. The bulb is clamped in the holder 33 as in the 45 holder 14, and the holders are used in the same manner.

The forward portion of the holder 14 may be 50 ornamented by fluting as shown in Fig. 3. However, it will be understood that the forward portions of the holders may be ornamented or decorated to suit various tastes and may be colored or otherwise treated as desired. Further, where a portion, as the portion 25 of holder 14 or 36 of holder 33 is to provide a reflecting surface it 55 will be apparent that such surface will be polished and plated if desired.

Having thus set forth the nature of my invention, what I claim is:

1. In a bulb holder for a flash light, a pair of 60 parts adapted to be detachably connected, the outer of said parts having an external screw thread for threading into the casing of a flash light, one of said parts having an opening of less diameter than a bulb whereby the portion of the part about the opening engages the globe por-

tion of the bulb and light from the latter may pass through the opening, and the other of said parts having an opening for the passage therethrough of the center contact of the bulb base and having its portion about said opening engaging 5 the bulb base to ground the same and whereby the bulb is clamped between the two parts of the holder.

2. A bulb holder comprising a pair of hollow 10 detachably connected parts enclosing a bulb and respectively engaging the globe and base portions of the bulb to clampingly support the latter, and said part engaging the globe portion of the bulb having an opening therein for the passage of light and having its portion about the opening 15 inclining inwardly and providing a reflector.

3. A bulb holder for a flash light comprising a pair of detachably connected hollow telescoping parts each including an end wall, said holder adapted to be disposed in an end portion of a 20 flash light casing, one of said parts having an opening in its end wall for the passage of light and having its portion about said opening arranged to engage the globe portion of a bulb, and the other of said parts having an opening in its 25 end wall for the passage of the center contact of the bulb base and having its portion about the opening engaging the bulb base to ground the same and whereby the bulb is clamped between the end walls of the holder.

4. In a device of the character described two 30 cupped members having telescoping threaded side walls, the end walls of said members each having an opening therein, and a light bulb having its glass end seated in one opening and its center contact extending through the other opening with the base contact engaging said end wall and grounded thereon.

5. A bulb holder for a flash light comprising a 40 pair of hollow detachably connected members, one of said members having a shoulder of less diameter than the globe portion of a bulb to engage the same, the other member having an end wall to engage the end of the bulb base to retain the globe portion of the bulb against said shoulder, said end wall of the second member also 45 having an opening for the extension therethrough of the center contact of the bulb, one of said members having an opening for the passage of light from said bulb, and means for securing said 50 members to a flash light casing.

6. A bulb holder for a flash light comprising two hollow members having telescoping threaded engagement, one of said members having a shoulder to engage the globe of a bulb, the other member having an end wall to engage the end of the bulb base to retain the bulb against said shoulder, said end wall also having an opening for passage therethrough of the center contact of the bulb, one of said members having an opening 60 for the passage of light from said bulb, and one of said members having an external screw thread for threading into a flash light casing.

7. A bulb holder adapted to be removably fitted to an end of a flash light casing, said holder comprising a pair of detachably connected parts respectively engaging the globe and base portions of a bulb and clampingly supporting the latter between them, one of said parts having an opening for the passage of light from said bulb, and one of said parts having an opening therein through which the center contact of the bulb projects for engagement with a contact in the casing.

8. In a device of the character described, a 70

holder comprising two cupped members having telescoping threaded side walls, the end walls of said members each having an opening, and a light bulb having its glass end seated in one opening and its base seated against the other end wall with its center contact extending through the opening therein, and said holder adapted to be threaded to a threaded portion of a flash light casing.

5 10 9. A holder for a flash light bulb including a base having a shoulder and a center contact at

one end, comprising a pair of hollow detachably connected members, one of said members having an annular shoulder of less diameter than the globe portion of the bulb to engage the same, the other member having an end wall to engage the shoulder of the bulb base to retain the globe portion of the bulb against said shoulder of the first member, and means for securing said members in a flash light casing.
